Primary Examiner — Robin V Webster(74) *Attorney, Agent, or Firm* — Robert C. Montgomery; Montgomery Patent & Design LP.(57) **CLAIM**

The ornamental design for an attachable diverter for a fire sprinkler head, as shown and described.

DESCRIPTION

FIG. 1 is a perspective front side assembled view of the attachable diverter for a fire sprinkler head, showing our new design;

FIG. 2 is a perspective front side disassembled view of the attachable diverter for a fire sprinkler head;

FIG. 3 is a perspective bottom side view thereof;

FIG. 4 is a front side view with the back side view being a mirror image thereof;

FIG. 5 is a left side view thereof;

FIG. 6 is a right side view thereof;

FIG. 7 is a top side view thereof; and,

FIG. 8 is a bottom side view thereof.

The broken lines represent a boundary area and form no part of the claimed design.
